DRAPE ANCHOR FOR PRESTRESSED CONCRETE

Zane P. Laurini, Dallas, Tex., assignor to Frank Holister,
Co., Inc., Dallas, Tex., a corporation of California

Filed May 8, 1967, Ser. No. 7,021

Term of patent 14 years

(Cl. D51—1)

FIG. 1

FIG. 2

FIG. 3

FIG. 4

FIG. 1 is a top plan view of a drape anchor for prestressed concrete showing my new design.

FIG. 2 is a side elevational view, partly in section, thereof,

FIG. 3 is a side elevational view taken at a right angle to FIG. 2, and

FIG. 4 is a bottom plan view.

I claim:

The ornamental design for a drape anchor for prestressed concrete, as shown.
